(57) **CLAIM**

The ornamental design for a blister pack for pharmaceuticals, as shown and described.

DESCRIPTION

FIG. 1 is a front-left-top perspective view of a blister pack for pharmaceuticals according to a first embodiment of the present invention;

FIG. 2 is a view from the top side thereof;

FIG. 3 is a view from the bottom side thereof;

FIG. 4 is a view from the left side thereof;

FIG. 5 is a view from the right side thereof;

FIG. 6 is a view from the front side thereof;

FIG. 7 is a view from the rear side thereof;

FIG. 8 is a front-left-top perspective view of a blister pack for pharmaceuticals according to a second embodiment of the present invention;

FIG. 9 is a view from the top side thereof;

FIG. 10 is a view from the bottom side thereof;

FIG. 11 is a view from the left side thereof;

FIG. 12 is a view from the right side thereof;

FIG. 13 is a view from the front side thereof; and,

FIG. 14 is a view from the rear side thereof.

Although the design is illustrated as transparent, the claimed invention may also be embodied as opaque.
